UNITED STATES PATENT OFFICE.

ALLAN C. SARGENT, OF WESTFORD, MASSACHUSETTS, ASSIGNOR TO C. G. SARGENT'S SONS CORPORATION, A CORPORATION OF MASSACHUSETTS.

DRIER.

Application filed March 10, 1921. Serial No. 451,152.

To all whom it may concern:

Be it known that I, ALLAN C. SARGENT, a citizen of the United States, residing at Westford, in the county of Middlesex and the State of Massachusetts, have invented a new and useful Drier, of which the following is a specification.

This invention relates to a drier for fibrous materials in which the stock is fed through continuously and loosened and dried as it passes through the machine. The principal objects of the invention are to provide a device of simple character for both conveying the stock through and loosening it up into a condition in which each fiber practically will be exposed to the drying action of the air introduced; and to provide improved means for directing the current of drying air through the stock. In general, the invention involves a construction which is very simple and inexpensive, has few parts, and is not likely to get out of order in use.

Reference is to be had to the accompanying drawings in which

Fig. 1 is a side elevation of a drying plant constructed in accordance with this invention;

Fig. 2 is a side elevation of the drying and conveying drum proper, the casing being shown with its front wall removed in order to illustrate the interior parts in elevation;

Fig. 3 is an end view of the same;

Fig. 4 is a central sectional view on an enlarged scale on the line 4—4 of Fig. 1;

Fig. 5 is a longitudinal central sectional view showing the ends of the device.

I have shown the invention as involving a casing 10 provided with a pair of shafts 11 extending longitudinally thereof but in an inclined direction. The shafts are driven from a pulley 12 by means of gearing 13 so as to rotate in the same direction.

Each shaft 11 is provided with a series of supporting rolls 14 and on these rolls is supported a conveying and drying drum 15. This drum consists of a cylinder of wire mesh or other open material that will allow the air to circulate through it but prevent the escape of the fibrous material. It is provided with a plurality of cylindrical bands 16 by which it is supported on the several pairs of rollers 14.

At one end the drum is provided with a cylindrical receiving projection 17 but both

ends of the drum are nearly closed. This receiving end is open enough to admit the stock from an ordinary fiber feeding device 18, the details of which are not shown herein as they may be of any desired type. The drum is also of similar shape at the lower end but is open enough to allow discharge of the material from that end 19 to a doffer apron 20 which carries it away. It will be noted that the drum 15 is located on an inclined axis, receives the material at the upper end, and discharges it by gravity and its rotary action at the lower end. It is also provided with longitudinal bars 21, each having a series of pins 22 located at an inclination toward the direction in which the drum rotates for picking up the fibrous material at the bottom, carrying it up around with them to the top, and then letting it drop back across the drum. This action results in opening up the fiber and holding it in loose condition.

Located between the two ends of the casing 10 I have shown a pair of Sturtevant pressure fans 25 although any other convenient number can be used. They operate to draw the air in along a passage 26, part of it coming in through a regulating damper 27 and part of it coming up through the drums as indicated by the arrows. This air is forced down through a heating unit consisting of a series of steam pipes 28, in the form shown. It is forced to circulate into the bottom of the drum through an opening or passage 29 which may be bounded by two walls 30 and 31. The heated air therefore passes up through the loose material, while that is in the act of falling and rising, and out through an opening 32 into the passage 26. This affords a very efficient and extremely simple drying device and one that has great durability and requires very little attention.

Although I have described and illustrated only a single form of the invention I am aware of the fact that modifications can be made therein by any person skilled in the art without departing from the scope of the invention as expressed in the claims. Therefore, I do not wish to be limited to all the details of construction and arrangements herein shown and described but what I do claim is:

1. In a drier for loose fibrous material, the combination of a rotary drum having

walls through which the air can circulate freely and provided with internal inclined straight pointed pins for carrying the stock upwardly and part way around as the drum 5 rotates, a heating unit adjacent to the drum between its ends, means for blowing air through said unit and into the drum near the bottom, and means for leading the current of air from the top of the drum 10 transversely back to said blowing means.

2. In a drier for fibrous materials, the combination of an inclined rotary screen drum having longitudinal rows of carrying pins projecting inwardly therefrom at an angle, 15 means for rotating said drum, means for

feeding fibrous stock into it at one end, a heating unit comprising a series of heating pipes at one side of the drum, a passage leading from the bottom of said heating unit directly to the bottom of the drum, a passage along the top of the drum having an air admitting opening at one end and opening into the top of the drum intermediate to its ends, and a fan for drawing the air through said passage from the drum and 20 forcing it down through the heating pipes. 25

In testimony whereof I have hereunto affixed my signature.

ALLAN C. SARGENT.
